UNITED STATES PATENT OFFICE.

JOHN W. PARSONS, OF OWENTON, KENTUCKY.

IMPROVEMENT IN HEAD-BLOCKS FOR SAW-MILLS.

Specification forming part of Letters Patent No. 57,180, dated August 14, 1866.

To all whom it may concern:

Be it known that I, JOHN W. PARSONS, of Owenton, Owen county, Kentucky, have invented a new and useful Improvement in Head-Blocks of Saw-Mills; and I do hereby declare the following to be a full, clear, and exact description thereof, reference being had to the accompanying drawings, making part of this specification.

My invention relates to devices for enabling the simultaneous or separate setting forward of the knees of two or more saw-mill head-blocks, and for the release of one or more knees from the setting motion, all of said motions being under control of the sawyer from a single position.

Figure 1 is a perspective view of a pair of head-blocks embodying my invention. Fig. 2 is a top view of the head-blocks without the knees.

A represents a part of the log-carriage. B B' are head-blocks attached thereto, and surmounted by ways or tracks b b' for the support and guidance of knees C C'. Projecting from the sole of each knee is a double ratchet-rack, D.

E is a rock-head, pivoted at e to the carriage or head-block, and armed with two pairs of pawls, F f F' f', of which one pawl, f or f', of each pair projects beyond its fellow, F or F', half the pitch of the rack-teeth.

Springs G G', projecting inwardly from the head-blocks, serve to press the pawls toward the rack D and cause them to engage in the teeth thereof. Both rock-heads E, and through them the pawls F f F' f', are capable of being simultaneously operated by a lever, H, acting through links I I' and rod J.

In order to enable the release of one or both the knees from the setting mechanism, I have provided in each head-block a cam, K or K', which, being partially rotated by means of lever L or L' and rods l or l', presses apart two tongues, M M', having studs m m', which, bearing outwardly against projections N from the pawls, serve to hold said pawls entirely clear of the racks, and thus enable the withdrawal or retraction of the liberated knee or the working of the other knee alone.

It is intended that the points of the several pawls shall be so adjusted relatively to each other as for the points of one pair to engage in their appropriate teeth midway of the intervals of engagement of the opposite pair, and in this way, although the teeth of the rack itself may be one inch apart and strong in proportion, a pawl is ready to engage every fourth of an inch, and in this way the adjustment of the knee in setting forward may be of any desired nicety.

I claim herein as new and of my invention—

1. The setting mechanism consisting of the double rack D and pawls F f F' f', capable of simultaneous or separate action, substantially as set forth.

2. The cam K, lever L, rod l, and tongue M, adapted for the optional release of both or either head-blocks, in the manner explained.

In testimony of which invention I hereunto set my hand.

JOHN W. PARSONS.
